UNITED STATES PATENT OFFICE.

FERDINAND BURCHARTZ, OF NEW YORK, N. Y., ASSIGNOR TO BURCHARTZ FIREPROOF-
ING COMPANY, INC., A CORPORATION OF NEW YORK.

HOLLOW BLOCK FOR BUILDING PURPOSES.

1,215,106.

Specification of Letters Patent.

Patented Feb. 6, 1917.

Application filed October 12, 1910. Serial No. 586,603.

To all whom it may concern:

Be it known that I, FERDINAND BUR-
CHARTZ, a citizen of the United States, and
resident of the borough of Manhattan, city,
5 county, and State of New York, have in-
vented certain new and useful Improve-
ments in Hollow Blocks for Building Pur-
poses, of which the following is a specifica-
tion.

10 My invention relates to hollow tubular
blocks for building purposes and has for its
object to provide a means for closing the
open ends of said blocks, and to make said
blocks and closing means as separate ele-
15 ments which may be easily and quickly com-
bined thus simplifying the manufacture and
cheapening the cost thereof, besides making
it possible to use said blocks with or without
the end closing means as may be desired.
20 My invention is further designed to con-
struct the blocks so that they may be readily
and equally spaced from each other with the
axes of adjacent blocks extending at an
angle to each other if desired, to secure two
25 way channels for the accommodation of re-
inforcing rods. My invention will be fully
described hereinafter and the features of
novelty will be pointed out in the appended
claims.

30 Reference is to be had to the accompa-
nying drawings in which Figure 1 is a longi-
tudinal section of my improved block on the
line 1—1 of Fig. 2; Fig. 2 is a cross section
thereof on the line 2—2 of Fig. 1; Figs. 3
35 and 4 are cross and longitudinal sections re-
spectively of another form of my invention;
Figs. 5 and 6 are cross-sections of two addi-
tional forms of my construction; Fig. 7 is a
detail view of the closing plate used in con-
40 nection with the block shown in Fig. 6; Fig.
8 is a longitudinal section of yet another
form of my block; Fig. 9 is a cross section
of a portion of a floor or ceiling showing
use of the block shown in Fig. 8; Fig. 10 is
45 a plan view thereof with the binder omitted;
and Fig. 11 is a view similar to Fig. 9 show-
ing blocks of the kind illustrated in Figs. 8,
9 and 10 with the axes thereof extending
parallel to each other instead of at an angle
50 as in Figs. 9 and 10.

Referring more particularly to Figs. 1
and 2 of the drawings the tubular block 10
is provided with a wall 11 through which a
channel or recess 12 extends lengthwise and
55 parallel with the axial opening 12^a of the

block. This channel 12 serves to accommo-
date the one end of closing plates 13 which
are inserted into opposite ends of said chan-
nel for a certain distance and then bent
at substantially right angles to completely
close or cover the opposite open ends of the
60 axial opening 12^a or in other words the open
ends of the block. These plates 13 are pref-
erably made of metal so as to be easily ma-
nipulated as above described. Instead of
having two separate plates 13, a single plate
65 may be substituted and passed through the
channel 12 so as to have its opposite ends
projecting beyond the opposite ends of said
channel 12. These projecting ends are then
bent at an angle in the same manner as here-
70 inbefore mentioned to cover the open ends
of the block. The channel 12 is preferably
a trifle wider than the width of the axial
opening 12^a of the block so as to be capable
75 of accommodating a plate or plates 13 a
trifle wider than said axial opening. Simi-
larly the portions of the plate or plates left
projecting beyond the opposite ends of the
channel 12 should preferably be of sufficient
80 length so that when bent as described the
free end thereof will extend beyond the said
axial opening of the block. Thus when the
end plates are in position they will overlap
the said axial opening 12^a throughout its pe-
85 riphery and completely close said open ends
against the admission of mortar or other
binding agent.

In the form of my invention shown in
Figs. 3 and 4 the channel 12 is replaced by
90 a dove tail open recess or channel 14 which
extends lengthwise of the wall 11 also par-
allel with the axial opening 12^a and serves
to receive means for closing the opposite
ends of the opening 12^a. These closing
95 means may be the same as those shown and
described with regard to Fig. 1, that is a
plate or plates 13, applied and used in the
same way although I may also employ the
specific arrangement illustrated best in Fig.
100 4. In this illustration a continuous strip of
fabric 14^a such as burlap, canvas or the like
is located in the recess 14 of each adjacent
block and passes across the open ends of the
axial openings 12^a beneath a strip 14^b lo-
105 cated between adjacent blocks at the bottom
of channels 14^c formed by arranging said
blocks in spaced relation to each other on
the usual temporary support. These strips
110 14^b are preferably made of the same mate-

rial of which the block is composed and extend throughout the channels 14^c either continuously or at intervals. The said strips 14^b serve by their weight to maintain the fabric 14^a in a taut condition that is under tension across the open ends of each block so as to prevent the cement or other binder 14^d from forcing said fabric into said blocks, the fabric thus serving to exclude said binder 14^d from the interior of the block. 5 When the cement or other binder is introduced into the channels 14^c it first covers the said strips 14^b and thus by its weight prevents the pressure of the binder which 10 is subsequently introduced from lifting said strips as pressure is exerted on the fabric at points opposite the open ends of the blocks. Otherwise this form of block is 15 the same as the one illustrated in Figs. 1 and 2. In the form of construction shown 20 in Fig. 5 the dove tail channel or recess 14^a instead of being located on the outer surface of the wall 11 and facing outward is located on the inner face of said wall 11 and faces inward. It is to be understood that end 25 plates 13 of the same general type and relative dimensions as those shown in Figs. 1 and 2 of the drawings may also be used in connection with the form of construction 30 shown in Fig. 5.

Referring now more particularly to Fig. 6 of the drawings it will be seen that two opposite walls 11^a of the block are each provided with an outwardly facing dove tailed recess or channel 15 extending lengthwise thereof. In this form of my invention the open ends of the block that is of the axial opening 12^a are completely covered or closed by U-shaped closing plates 16 the 40 parallel portions 16^a of which closing plates are inserted into the opposite ends of the recesses 15. It is of course to be understood that instead of the dove tailed recesses 15 the opposite walls 11^a of this form of block 45 might each be provided with a channel similar to the channel 12 of Fig. 1. It is to be further understood that in each of the forms of my invention so far described the channel or dove tailed recess need not extend 50 throughout the entire length of the block, but may only extend inwardly a distance from each end in the nature of separate channels or recesses. It is to be understood that if desired instead of the plate or plates 55 13 a fabric closing medium of the kind shown in Figs. 3 and 4 may also be used in connection with the forms of my invention shown in Figs. 1, 2, 5 and 6.

In the form of my invention shown in 60 Figs. 8, 9, 10 and 11 the block 10 in addition to having a channel 12^b corresponding to the channel 12 of Fig. 1 is provided with a preferably integral projection 21 extending longitudinally of the upper surface of the 65 block and preferably provided with a chan-

nel 21^a projecting lengthwise of the projection. The width of this projection is somewhat less than the width of the block and said projection is preferably arranged in the center of said block which extends equally 70 to each side thereof. End closing devices of the same kind as hereinbefore described that is metal or other plates or strips of fabric are also used in connection with this form of block to seal the open ends thereof 75 in the same way as already brought out.

The blocks in all the forms of my invention are preferably formed with flanges 22 extending parallel with the axis at opposite lower edges of each block. Thus when the 80 blocks are set up on the temporary scaffolding these flanges serve to equally space the blocks to form channels hereinbefore referred to as 14^c. The blocks are preferably arranged with the axes of adjacent blocks 85 extending at an angle to each other so that the flanges of one block will abut against the closed ends of the next adjacent block as clearly shown in Figs. 9 and 10 and thus 90 form channels extending in two directions and crossing each other. The usual tie rods 23 are placed in these channels preferably upon said flanges 22 after which the mortar or any other binding agent 14^d is introduced 95 therein in the usual way so as to fill said channels and in some cases also to cover the upper surfaces of the blocks. This binding agent will enter any space between the closing devices and the blocks and will thus 100 securely bind the blocks and various end closing devices into single solid structures. If the block illustrated in Figs. 8, 9, 10 and 11 is used the projections 21 will interrupt the cement or other binder 14^d which covers the upper surfaces of each block to each 105 side of its projection 21, but is flush with the upper surface of said projections. Some of the binder will enter partly into the channels 21^a and serve to more firmly bind the entire elements into a single solid structure. 110 If desired, however, the blocks particularly when the form shown in Fig. 8 is used, may be placed adjacent to each other with the axes arranged parallel and the flanges of adjacent blocks abutting against 115 each other to space the blocks. With this arrangement which is shown in Fig. 11 the channels for the tie rods and binder extend only in one direction and the binder 14^d in 120 each channel is also interrupted by the projections and forms a T beam extending throughout the length or width of the floor as the case may be. With the arrangement shown best in Fig. 9 the binder in the channels is in the shape of an inverted L although as some of said binder enters partly 125 into the channels 21^a a substantially T shaped cement or other beam is also secured. The said binder, however, in all forms of 130 my invention is prevented by the end clos-

ing devices from reaching the main portion of the interior of the block and also serves to securely lock said devices in operative position. A light and very strong and durable floor or ceiling construction of great carrying and resisting power is thus secured. It is of course to be understood that material other than metal may be used in constructing the various forms of end closing plates.

Furthermore instead of being solid said closing plates might be made of wire netting or other perforated or foraminated material. In the forms shown in Figs. 3, 4, 5, 6, 8, 9, 10 and 11, the closing plates or fabric as the case may be and the recesses or channels for the accommodation thereof are so proportioned as to overlap the periphery of and thus completely close the open ends of each block in the same manner as described with regard to Figs. 1 and 2.

It is to be understood that the term "tubular block" as used in the claims is used in a broad sense and is intended to cover a block of any cross sectional configuration or shape.

It is further to be understood that all forms of my closing devices may be used in conjunction with ordinary open ended blocks. In other words the various recess or channel forming means may be entirely omitted. When used with such blocks the plates 13, etc., are simply placed over the open ends of the block with the horizontal portion of such plates in engagement with the upper surface of the block, or in case the fabric closure is used, this fabric is simply stretched or laid over said upper surface and then brought down over the open ends of the block in the same manner as shown and described with regard to Figs. 3 and 4 of the drawings.

Various changes in the specific forms shown and described may be made within the scope of the claims without departing from the spirit of my invention.

I claim:

1. A building block provided with an axially extending opening, and a closure comprising a substantially rectangular member of substantially even dimensions throughout and of greater width than said opening, said member being shaped to form a substantially right angled element, one leg of which lies in surface engagement with

an axial surface of said block and the other leg of which extends over an open end of the axial opening whereby the latter is completely covered.

2. A building block provided with an axially extending opening and a channel located above the same, said channel being greater in width than said opening and being less in vertical dimension, and a closure comprising a substantially rectangular member of substantially even dimensions throughout and shaped to form a substantially right angled element, one leg of said element extending into and fitting said channel and the other leg extending over an open end of the axial opening whereby the latter is completely covered.

3. In a floor or ceiling construction, a series of open ended blocks arranged in rows in axial alinement and spaced from each other to form channels, a continuous strip of fabric extending lengthwise of each row along one face of the blocks therein, across the open ends thereof and across the channels below the end openings of the blocks and means in said channels for maintaining the strips under tension against and across said open ends.

4. In a floor or ceiling construction the combination of a plurality of blocks arranged in rows and spaced apart to form intersecting channels, said blocks being each provided with a plurality of axially extending passages, beams of coalescent material in said channels and engaging said blocks on all sides and extending into some of said passages and means for closing the other passages against the entrance of coalescent material.

5. A building block provided with an axially extending opening and a channel extending parallel therewith, and a closure comprising a substantially rectangular member shaped to form a substantially right angled element, one leg of which extends into said channel and the other leg of which extends over an open end of the axial opening whereby the latter is closed.

In testimony whereof I have hereunto set my hand in the presence of two subscribing witnesses.

FERDINAND BURCHARTZ.
